HERNIA PAD

Fred E. Moore, Los Angeles, Calif.

Application August 19, 1935, Serial No. 36,838

3 Claims. (Cl. 128—114)

This invention relates to a pad to be used for amelioration of a hernia.

Pads of various kinds for this purpose have been proposed; but all of them have inherent disadvantages. These pads serve merely as a support, with no attempt to assist or accelerate the normal curative powers of the sufferer. Accordingly, pads of this character are usually worn over indefinite periods, and are not only 10 decidedly uncomfortable, but cause very annoying irritation.

It is one of the objects of this invention to provide a pad that overcomes these disadvantages.

15 It is another object of the invention to make it possible, by means of the pad, to aid the recuperative powers of the patient in repairing the rupture.

These results are accomplished by providing 20 a pad made in such form that it can adequately support the hernia and yet permit blood circulation to the membranes adjacent the hernia. In this way, the recuperative powers of the body are permitted to rebuild and repair the membranes around the hernia, and thereby a cure 25 is in many cases effected. The pad of this invention, accordingly, is not merely a palliative, but is an active agent assisting in the cure of the trouble.

30 This invention possesses many other advantages, and has other objects which may be made more easily apparent from a consideration of several embodiments of the invention. For this purpose there are shown a few forms in the 35 drawing accompanying and forming part of the present specification. These forms shall now be described in detail, illustrating the general principles of the invention; but it is to be understood that this detailed description is not to be taken in a limiting sense, since the scope of the invention is best defined by the appended 40 claims.

Referring to the drawing:

Figure 1 is a perspective view of a pad incorporating the invention shown as supported upon a truss of conventional form;

Fig. 2 is an enlarged sectional view taken along the plane 2—2 of Fig. 1;

Fig. 3 is a top plan view of the pad incorporating the invention; and

Fig. 4 is a perspective view of a slightly modified form of the invention.

The truss structure 1 is adapted, as is well understood, to encompass the lower portion of the trunk of the wearer. It is usually provided

with one or more slots such as 2 for supporting a hernia pad. This hernia pad is shown to best advantage in Figs. 2 and 3.

The hernia pad 3 is shown as being made from porous resilient or yielding material, such as 5 sponge rubber. It has a generally convex active surface 4 adapted to contact with the body of the patient. The truss structure 1 is adapted, as is well understood, to urge the apex of the pad 3 firmly against the hernia. 10

In pads that have been in common use heretofore, a soft or yielding material has been utilized and their main function has been merely to support the hernia without any attempt actually to assist in the cure of the hernia. As is 15 well understood for example in abdominal hernia, the membrane supporting the intestines is weakened or ruptured so that a portion of the intestines protrudes and forms a lump. It has been found that by proper design of the pad, not only 20 is it possible to hold the intestines inside of the abdomen, but also to assist in the knitting together or strengthening of the walls of the supporting membrane, so that ultimately the pad 25 can be discarded and a cure effected.

To secure this result the area of contact between the pad 3 and the affected part of the body is so defined that circulation of blood adjacent this portion of the body is not materially impeded and air is permitted to circulate over the 30 affected portions adjacent the point of contact.

For this purpose a plurality of grooves 5 is provided which converge generally toward the apex of the pad. These grooves diminish in depth as the apex is approached, as shown most 35 clearly in Fig. 2. By virtue of these grooves the pad is worn with a greater degree of comfort than those heretofore utilized by hernia patients.

The pad 3 is furthermore made hollow providing a concave inner surface 6 adapted to overlie a supporting member 7. This supporting member 7 can be appropriately formed of Bakelite and serves as a cover for a body member 8. This body member 8 has an exterior thread 9 engaged by the depending edge 10 of the cover member 7. Furthermore the supporting body 8 has a recess or cavity 11 forming a space for the accommodation of medicinal liquid. This medicinal liquid is adapted to be fed gradually to the contacted area of the patient's body, as 45 by the aid of an aperture 12 in the top of cover member 7. This aperture 12 is alinement with a small central aperture 13 through the pad 3.

The pad 3 at its base is provided with the inturned integral flange 14 whereby the pad is 55

supported between the edge 10 of cover 7 and the flange 15 of the supporting body 8. The flange 14, together with the body 8, also serves to maintain the base of the pad against deformation due to pressure exerted on the apex 4. This is an important feature, since by maintaining the convex configuration of the pad, it ensures that the pressure exerted by the apex will be confined to a relatively small area of the body 10 of the wearer, and further, that the grooves 5 will be maintained open, and will not be obstructed by their sides coming together, as would occur if the pad was allowed to collapse. The pad 3 being yielding and resilient, can easily be 15 removed from the supporting structure and replaced thereon by merely stretching it over the cover 7.

In order to support the pad structure including the pad proper 3 and the supporting structure 20 7 and 8 upon the truss 1, a post 16 can be molded into the body 8 which is preferably made from Bakelite or similar material. This post is threaded and has a collar 17 contacting with the lower surface of the body 8. The post passes 25 through a slot 2 in truss 1 and a thumb nut 18 is utilized to hold the pad structure in place. This thumb nut 18 can be provided with a loop 19 for turning the nut 18.

Should it be desired to utilize liquid medicine, 30 it is a simple matter to remove the pad 3 and unscrew the cap 7 for exposing the recess 11. Such medicine may be advisable at times for soothing the skin and prevent irritation.

The particular configuration of the pad 3 can 35 be varied to suit specific conditions. For example, in the form shown in Fig. 4, a pad is illustrated having a higher apex and, therefore,

adapted to extend somewhat deeper into the affected portion of the body.

I claim:

1. In a device of the character described, a hollow pad made from porous yielding material, 5 and having a convex active surface, said surface having grooves therein generally converging toward the apex of the surface, said pad having a lower inwardly directed flange, and a hollow rigid support for said pad, comprising a cover 10 member having a depending edge, and a body member, said flange being adapted to be inserted between the depending edge of the cover member and the body member, said cover member being removable for placing liquid into the support, 15 said cover member having an aperture for the discharge of the liquid to the pad, said pad having an aperture in communication with the cover aperture.

2. In a device of the character described, a 20 hollow externally threaded support, a cover disposed over the support, said cover being provided with a depending interiorly threaded edge adapted to engage the support, and a yielding pad having a flange engaged beneath the depending edge.

3. In a device of the character described, a hollow threaded support, a cover disposed over the support, said cover being provided with a depending threaded edge adapted to engage the 30 support, and a yielding pad having a flange engaged beneath the depending edge, said pad being made from sponge rubber and having an aperture in communication with an aperture in the cover.

FRED E. MOORE.
